RAILWAY CAR JACK

Bernard R. Picard, Fort Dodge, Iowa

Application May 1, 1941, Serial No. 391,423

3 Claims. (Cl. 254—33)

This invention relates to a railway car jack and has for an object to provide a device of this character which will raise the truck side of a railway car to permit removal of wedges and brass for inspection and for other purposes, the device being so constructed as to increase the speed of inspecting wedges and brass over similar devices now in use.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming a part of this specification:

Figure 1 is a side elevation of a railway car jack constructed in accordance with the invention showing the pneumatic cylinder tilted back, in dotted lines, to counterbalance the beam for easy transportation.

Figure 2 is a plan view of the railway car jack shown in Figure 1, with parts removed.

Figure 3 is a rear elevation of the railway car jack with parts in section.

Figure 4 is a front elevation of the railway car jack.

Figure 5 is a detail plan view of the lifting beam of the jack.

Figure 6 is a detail vertical sectional view taken on the line 6—6 of Figure 1.

Referring now to the drawings in which like characters of reference designate similar parts in the various views, 10 designates a beam of Y-shape, see Figure 5, preferably formed of channel iron and adapted to pass underneath the center of the truck side on top of the rail and act as a lever, with the rail as a fulcrum to raise the truck side, indicated at 11 in dotted lines in Figure 1. The branches of the beam are turned with their open sides toward each other and the open sides are closed by a V-shaped plate 12. The channel irons forming the shank of the beam are disposed with their open sides contacting each other, see Figure 5, and a plate 13 is disposed on top of the channel irons adjacent to the branches of the beam to support a post 14, see Figures 1 and 6.

The post 14 comprises a base plate 15, see Fig-

ure 6, which is slidably mounted on the plate 13, and is provided at the ends with downwardly extending wings 16 which are disposed on opposite sides of the beam to prevent the post from slipping laterally on the beam. A short length of pipe 17 is welded or otherwise secured to the base plate 15 in which is disposed a longer pipe 18 which is also welded or otherwise secured to the base plate. The two pipes form a support to 10 interchangably receive pipes 19 of relatively different heights which are closed at the top by a plate 20 adapted to engage underneath the side frame of the car truck. The front end of the beam is provided with a handle 21.

A pneumatic cylinder 22 of relatively large capacity is mounted at the rear ends of the branches of the beam and is closed at the top by a cover 23, see Figure 3. The cylinder is provided with an inverted frustum shaped bottom 24 having a guide boss 25 and having a vent opening 26. A piston 27 is disposed within the cylinder and is provided with a downwardly extending piston rod 28 which projects through the boss 25 and below the boss is equipped with a foot 29 which is normally held raised above the ground by a helical spring 30 which is sleeved on the piston rod 28 between the upper surface of the boss 25 and the underneath side of the piston 27. When motive fluid is let into the cylinder above 25 the piston, the piston is forced downward to force the foot 29 against the ground and elevate the cylinder and the beam at the rear end so that the beam fulcrums on the rail 31, see Figure 1, and raises the post 14 to lift the side of the truck 30 and permit inspection of the wedges and brass.

The cylinder is secured to the branches of the beam through the medium of pins 32, which are engaged through the branches and V-shaped plate 12. Links 33 are welded or otherwise secured at the upper ends to a flange 34 formed on the inverted frustum shaped bottom 24 of the cylinder. The links are provided with openings 35, one of which is shown in Figure 3, to pivotally receive the pins 32 so that the cylinder may be 40 disposed upright on the branches of the beam, or may be rocked rearwardly to the dotted line position shown in Figure 1, to counterbalance the weight of the beam and promote easy transportation of the device.

50 A strap bracket 36 is secured at one end to the flange 34 of the cylinder 22 and is adapted to engage the plate 13 of the beam to hold the cylinder in upright position. A cross bar 37 is welded or otherwise secured to the cover 23 of the cylinder and projects at both ends beyond

the cylinder to engage with upwardly and rearwardly inclined handle bars 38 to support the cylinder in rearwardly inclined position, see Figure 1.

The handle bars are connected at the front ends to channel brackets 39, see Figure 3, which have their webs welded or otherwise secure to the webs of the channel brackets forming the branches of the beam, see Figures 3 and 5. The channel brackets 39 also carry stub axles 40 to which ground wheels 41 are secured for transporting the device.

Fluid pressure supply and release connections 42 enter the cover of the cylinder above the piston and are provided with respective hose 43. The hose connections are controlled by valves 44.

To hold the front end of the beam against displacement from the rail, a pair of stop members 45 and 46, in the nature of transversely extending cleats, are disposed on the bottom face of the front end of the beam. The cleats are adapted to lie along the inner and outer sides of the head of the rail, see Figure 1, and prevent displacement of the beam from the rail.

Since the operation of the parts has been described as the description of the parts progressed, it is thought the invention will be fully understood without further explanation.

What is claimed is:

1. A railway car jack comprising a beam, a post slidably mounted on one end of the beam, a pneumatic cylinder pivotally mounted on the other end of the beam for movement to an upright position and to a rearwardly inclined position, handle means extending from the rear end of the beam, a stop member connected to the cylinder engageable with the handle means for holding the cylinder in rearwardly inclined position, a stop member connected to the cylinder engageable with the beam for holding the cylinder in upright position, ground wheels connected to the beam for transporting the device, a piston rod extending through the bottom of the cylinder, a shoe on the bottom of the piston rod adapted to contact the ground, a spring sleeved on the piston rod within the cylinder normally holding the shoe raised above the ground, and means for admitting a fluid pressure medium to the cylinder above the piston to raise the cylinder off the piston when the shoe rests upon the ground and carry the rear end of the beam upwardly to cause the forward end of the beam to fulcrum on a rail and move the post upwardly to raise the truck side of a railway car.

2. A railway car jack comprising a beam of

Y-shape adapted to rest at its front end upon a rail of a track underneath the center of the truck side of a railway car and form a lever fulcruming on the rail, an upright cylinder on the rear end of the Y-shaped beam, a piston within the cylinder, a shoe connected to the piston and disposed exteriorly of the cylinder adapted to rest upon the ground, a connection between the cylinder and the branches of the beam, bars secured to and extending upwardly from the branches of the beam, handles extending upwardly and rearwardly from the bars, ground wheels carried by the bars forming means by which the jack may be conveniently moved from place to place, a spring within the cylinder normally holding the piston raised for holding the shoe off the ground, means for admitting a fluid pressure medium to the cylinder above the piston to raise the cylinder off the piston when the shoe rests upon the ground and carry the rear end of the beam upwardly to cause the forward end of the beam to fulcrum on a rail and move the post upwardly to raise the truck side of a railway car, stop means on the front end of the beam adapted to contact with a rail head and hold the beam against displacement from the rail, and a post extending upwardly from the front end of the beam adapted to contact with the truck side of a railway car and raise said truck side when fluid pressure medium is let into the cylinder.

3. A railway car jack comprising a beam adapted to rest at its front end upon a rail of a track underneath the center of the truck side of a railway car and form a lever fulcruming on the rail, an upright cylinder on the rear end of the beam, a piston within the cylinder, a shoe connected to the piston and disposed exteriorly of the cylinder adapted to rest upon the ground, ground wheels carried by the beam, means for admitting fluid pressure medium to the cylinder above the piston to raise the cylinder, the rear end of the beam and the ground wheels off the ground when the shoe is disposed on the ground to rock the beam upwardly at the rear end, means on the front end of the beam for preventing displacement of the beam from the rail during rocking of the beam on the rail as a fulcrum, and a post slidably mounted on the front end of the beam adapted to contact with the truck side of a railway car and raise said truck side when fluid pressure medium is let into the cylinder.

BERNARD R. PICARD.
